UNITED STATES PATENT OFFICE.

EDMUND C. MORGAN, OF NEW YORK, N. Y.; OLIVE EUGENIE MORGAN EXECUTRIX OF
SAID EDMUND C. MORGAN, DECEASED.

MINING MACHINE.

Application filed October 11, 1922. Serial No. 593,727.

To all whom it may concern:

Be it known that I, EDMUND C. MORGAN, a citizen of the United States, residing at New York, in the county of New York and State of New York, have invented certain new and useful Improvements in Mining Machines, of which the following is a specification.

This invention relates to machines for mining coal and similar material and is a continuation in part of my co-pending application, Serial No. 121,359, filed September 21, 1916, granted February 17, 1925, Patent No. 1,526,558 for an improvement in mining machines.

One of the objects of the present invention is the provision of a mining machine which shall be of improved construction and more efficient in operation than previously known machines.

The invention is exemplified in the combination and arrangement of parts shown in the accompanying drawings and described in the following specification, and it is more particularly pointed out in the appended claims.

In the accompanying drawings—

Fig. 1 represents a sectional elevation view of a mining and loading machine with my invention applied thereto;

Figs. 2 and 3 are diagrammatic views showing different cross-sectional shapes of mine chambers formed by the mining machine illustrated in Fig. 1;

Fig. 4 is a vertical sectional view approximately on the line 4—4 of Fig. 1 with the movable motor in its forward position;

Fig. 5 is a front elevation of one of the loop chain core-cutters;

Fig. 6 is a cross-sectional view of a supporting bar for the chain cutter;

Fig. 7 is a transverse sectional view on the line 7—7 of Fig. 5;

Fig. 8 is a fragmentary elevational view showing a supplementary frame in position for changing one of the chain cutters on the plane kerf-cutter;

Figs. 9 and 10 are side elevation and top plan views, respectively, of a supplementary chain replacing frame;

Fig. 11 is a sectional view on the line 11—11 of Fig. 8;

Fig. 12 is an elevational view of mechanism for moving a flexible cutter chain onto

or off from the cutter frame of the loop chain cutter; and

Fig. 13 is a sectional plan view taken on the line 13—13 of Fig. 12.

Referring to Fig. 1, 25 designates a supporting base plate on which are mounted the various parts of the mining machine. Extending upwardly from opposite sides of the rear portion of the base plate are two hydraulic cylinders 26 for varying the elevation of a bearing member 29 to which is pivoted at 30 the side plates 88 of the mining machine frame 32. By the combined action of the jack 36 and the jacks 26 the mining machine may be adjusted vertically in the mine chamber with the cutterhead base plate 32 in a horizontal plane, or the cutting mechanism may be tilted to various angles. For instance, in Fig. 1 the cutting mechanism is tilted toward the roof by causing the jack 36 to lift the mining machine and operating the jacks 26 so as to lower the rear end of the mining machine.

Mounted on the box frame 33 are separate chain cutters illustrated at 40 in Figs. 1 and 4, and at 42 in Fig. 5. The cutter chain 40 is carried on a frame 43 which has a forward and backward sliding movement on the vertical central plane of the cutter-head. The frame 43 is supported at its rear end by a pair of bracket members 44 which depend from a horizontal plate 45. The plate 45 is mounted to slide between guideways 46 formed on the upper inner portions of the side members on the box frame 33, as shown in Figs. 1 and 4. Also supported by and depending from the plate 45 is a motor 47 connected by gears 48 to a cross-shaft which carries a sprocket wheel 51. The chain cutter 40 slides on the frame 43 and passes around the sprocket 51 and is thus driven by the motor 47 which is mounted to slide forwardly and backwardly along the central plane in the machine, together with the chain 40 and its supporting frame.

Longitudinal reciprocation of the cutting mechanism thus formed is produced by a hydraulic motor 55 carried on a plate 56 secured by bolts 57 to the upper portion of the box frame 33. The piston rod 58 of the cylinder 55 connects with an upwardly extending lug 59 formed integral with the upper portion of the sliding plate 45. It is evident that movement of the piston rod 58 in the

cylinder 55 will reciprocate the cutter chain 40 in the longitudinal direction of the mining machine.

The cutter chain 42 is carried by a loop shaped cutter frame 60 having an unobstructed core-opening extending therethrough and mounted for horizontal pivotal movement about an upright axis at one side of the box frame 33. There are in reality 5 two of such loop chain core-cutters mounted for operation in opposite directions toward each other with the plane kerf-cutter 40 provided for severing the crescent-shaped core sections cut by the two loop chain core-cutters. However, only one loop chain core-cutter is shown in the accompanying drawing because the appended claims are directed to the mechanism for renewing the chain cutters, while the combinations including the 10 chain cutters are covered in the aforesaid application, Serial No. 121,359.

The loop-shaped core-cutter frame 60 is secured to the outer side of a swinging bracket 62 provided with a bearing 63 mounted on the journal 61 about which the loop-shaped core-cutter swings. The gear segment 64 is secured to the bracket 62 adjacent the pivotal support 61 and meshes with a rack 65 carried by a plunger 66 fitting within a hydraulic cylinder 67 carried by the plate 56. The reciprocation of the plunger 66 in the cylinder 67 operates the gear segment 64 to swing the core-cutter about the upright axis 61 to feed said core-cutter into the coal.

The bracket 62 is provided with a shoulder 68 which bears upon an arcuate-shaped slideway 69 secured to the front portion of the box frame 33, as shown in Fig. 4. This 20 slideway supports the bracket 62 and the loop chain core-cutter as they are swung about the axis 61.

The loop chain core-cutter 42, as shown in Fig. 5, is driven by a sprocket wheel 70 journaled for rotation on a shaft 71 in the bracket 62. The shaft 71 is driven by means of gearing in the gear casings 79, 80 connected to the shaft 81 of the electric motor 82.

The base plate 32, as shown in Fig. 1, is provided with a sliding extension plate 90 for the purpose of closing the gap between the forward edge of the plate 32 and the mine wall being operated on. This is desirable in order that there will be no opening left between the plate and the wall of the chamber through which the severed material may fall as it is being drawn backwardly toward loading position. The extension plate 90 is provided with a suitable depression 91 in the upper surface of the plate 32 through which it slides, the rear edge of the depression being beveled in order that no particles of material may be caught between the rear edge of the plate

90 and the shoulder formed by the depression 91.

In order to move the cuttings formed by the cutter chains rearwardly to a position from which they may be conveyed away, a 70 conveyer chain 100 having flights 101 is mounted to move over the upper surface of a portion of the base plate 32 adjacent the emerging runs of the chain cutters. The chain 100 is guided by a shoulder 103 formed on the base plate 32 and by an overhanging flange 104 formed on the lower surface of the box frame 33. An upwardly extending ridge 105 having its outer edge gradually sloping, extends around the outer periphery of the path of movement of the flights 101 to prevent escape of material as it is carried by movement of these flights. The chain 100 is driven by a sprocket wheel 106 carried on an upright shaft 107 and connected by worm gearing 108 to a motor 109 mounted on the base plate 32.

As shown in Fig. 1, the cutterhead base plate 32 is cut away at its rear portion, as indicated at 110, and through the opening thus formed the material escapes as it is drawn backwardly by the discharging apparatus. The material thus discharged is received in a hopper 111 held by a flange plate 112 to the base plate 32 and free to rotate thereon about an upright axis. An endless conveyer 113 is arranged to carry material from the hopper 111 rearwardly to a position where it may be discharged into a mine car. A guard plate 114 is provided for engaging the opening between the cutterhead base plate 32 and the upper edge of the hopper 111. This plate 114 is pivoted in slots 115 in the side plates 88 and normally rests in the position shown in Fig. 1, it being held from further downward pivotal movement by stops or abutments 116. It is evident that the entire guard plate 114 may move upwardly between the side walls 88 when the cutterhead frame is moved to its lowermost position.

From time to time during the operation of a mining machine of this character it is necessary to replace or sharpen the bits of the cutting chains. For this purpose the loop chain core-cutter frame 42 may be swung rearwardly and the chain removed, as illustrated in Fig. 12, and as hereinafter described. It is more difficult to reach the 115 chain cutter 40, however, since it operates to cut a vertical intersecting kerf in advance of the mining machine frame to sever the core sections into two parts for movement along opposite sides of the machine toward the hopper 111. In order that the chain 40 may be removed and a duplicate chain substituted having new cutting bits, the device illustrated in Figs. 8 to 11, may be provided. This device consists of a 120 frame having an upper chain guide 135 and

a lower chain guide 136. Supporting standards 137 are provided for the frame shown in Fig. 9. These standards 137 may be secured as indicated at 137' to the upper surface of the box frame 33.

In Fig. 8 the unshaded links represent the old chain which is to be removed from the frame 43 and the shaded links carried by the guides 135 and 136 represent the chain which is to replace the used chain. Two of the links of the used chains are separated and the ends thus formed are connected with the ends of the chain to be substituted. After this is done the motor 47 is operated to cause the two chains to interchange places, after which the old chain is disconnected and removed and the free ends of the new chain connected, thus leaving the new chain in position to continue the cutting operation. When the interchange is completed the supplementary chain carrier may be removed from the top of the machine and the mining operations proceeded with as before. However, if desired, the guide frames 135 and 136 may be left permanently connected to the frame 33 and the operating length of the chain cutter doubled so as to be guided during operation along both the frame 43 and the detachable guide frame. As the frame 43 moves forward during the feeding operation the upper run along the guide frame 135 will lengthen, but the lower loop at the rear end of the frame 43 will shorten proportionately so that during the forward feed of the chain cutter one portion will be paying out while the other portion is being taken up, thus retaining proper tension in the chain without permitting it to become unduly slack. But even when the double length of chain is used during operation it may be renewed by first substituting a new chain length for a half portion thereof and then substituting another new length for the other half portion of the chain. This can readily be done, because by comparing Fig. 8 with Fig. 1 it will be seen that the rear end of the guide frame 135, 136 extends to a position near the rear end of the frame 33 which is in convenient position for the attendant.

In order that the chain 42 may be readily removed from the guide frame 60 the latter, as shown in Figs. 6 and 7, is provided with notches in which the chain slides, the notch being of such shape that the chain when loosened may be moved bodily in an outward direction away from the cutter frame bar without removal of any retaining strips or similar devices. The cutter frame bar 60 is provided with a notch 140 and a peripheral flange 141 which cooperates with the flange 142 and the notch 143 formed in the links of the cutter chain 42. It is clear that when the chain is stretched about the frame 60 the tension on the chain will

prevent it from moving outwardly away from the guide frame. When it is desired to remove the chain it may be sufficiently slackened by an adjustment of the frame or by disconnecting the links of the chain so that the latter will move readily in an outward direction from the frame a sufficient amount to permit the removal of the chain from the frame.

In Figs. 12 and 13 I have shown mechanism for removing from a loop chain core-cutter a used chain and substituting therefor a chain with newly sharpened bits. This is particularly desirable when the chain has interlocking guiding connections with the cutter frame so that the chain can not be removed laterally therefrom, as illustrated in Figs. 5, 6 and 7. Referring to Figs. 12 and 13 it will be seen that at the top of the frame 62 are secured spaced-apart L-shaped angle bars 144 for receiving the pedestal 145 of mechanism for supporting two chain reels 146 and 147. The reel 147 is mounted on the journal bearing sleeve 148 at the upper end of the pedestal 145. The sleeve 148 is mounted to rotate on the journal bearing 149 and connected to the sleeve 148 is a disc 150 in position to be engaged by the driving wheel 151.

The reel 146 is mounted on the sleeve 152 which in turn is mounted on the journal bearing 153. The sleeve 152 is connected to the disc 154 in position to be engaged by the friction wheel 151. Resilient mechanism is provided for holding the friction wheel 151 in yielding engagement with the small disc 154 on the sleeve 152 and with the larger disc 150 which is secured to the sleeve 148. Pivoted at 155 is a rod 156 with a nut 157 at its upper end. Between this nut 157 and an arm 158 is a spring 159. The arm 158 is pivoted at 160 to the auxiliary supporting frame 161. The other end of the arm 158 carries the friction wheel 151. The opening 162 in the arm 158 is of such size and shape as to permit free up and down movement of the friction wheel 151 which is yielding held in engagement with the disc wheels 154 and 150 by means of the spring 159.

A belt 163 is adapted to be secured to the hub of the reel 146 and wound thereon. This belt 163 is adapted to be connected at 164 to one of the disconnected links of the chain 42, the other end of the disconnected chain being connected to a new chain 42' on the reel 147. The latter is also provided with a belt 163' having one end secured to the hub of the reel and the other end secured at 164' to the chain 42' which is wound on this reel.

Upon connecting the chains in the manner indicated in Fig. 12 the sprocket wheel 70 may be driven by the motor 82 and the gearing connected to the shaft 71, in such

a direction as to unwind the chain from the reel 147. Motion will then be transmitted simultaneously through the friction wheel 151 to the reel 146 to wind the belt 163 thereon and subsequently the old chain is removed from the core-cutter. It should be noted that while the reel 147 is rotated in an anti-clockwise direction to unreel the chain 42' therefrom the motion transmitted by the wheel 151 to the reel 146 is such as to cause the reel 146 to be rotated in an anti-clockwise direction to wind the old chain thereon. Preferably the gear ratio is such as to cause the reel 146 to take up the chain as fast as it is paid out by the reel 147. The disc wheel 150 is therefore of larger diameter than the disc wheel 154. As the chain is paid out from the reel 147 the diameter of the convolutions of the chain on the reel grows gradually less while at the same time the diameter of the convolutions of the reel 146 grows gradually larger. The rotation of the wheel 147 therefore gradually diminishes in speed while less speed is required for taking up the chain on the reel 146 on account of the gradually increasing diameter of the convolutions thereon. However, the tension on the old chain being removed or on the new chain being substituted therefor can not become too great because whenever there is any tendency in this direction the friction wheel 151 will slip on the disc 150 or on the disc 154 by reason of the yielding support for the friction wheel 151 comprising the spring 159.

While the new chain is being unreeled from the reel 147, the lateral extension 165 from the standard 145 may be relied on to properly guide the chain 42 onto the core-cutter frame.

It should also be noted that the reels 146 and 147 are detachable from the sleeves 152 and 148, respectively. When the reel 146 has the old chain wound thereon, such chain is disconnected from the substituted chain and the ends of the latter connected together to form the endless traveling loop core-cutter chain. The reel 146 with the old chain wound thereon may be removed from the sleeve 152 and sent with the chain in a very compact form to the repair shop where the cutter bits may be removed and sharpened and then brought back in a very compact form on the reel, as illustrated at 147 in Figs. 12 and 13 and placed on the sleeve 148. Not only may the old and new chain lengths be transported in very compact form, but after the bits are sharpened they may be transported while the sharpened bits are amply protected until ready to be placed on the loop chain core-cutter frame in place of an old chain with dull bits thereon. Preferably the framework 145, 161 for supporting

the reels is detached from the machine after the chain with sharpened bits has been substituted for a chain cutter which has been used for some time. After the framework 145, 161, together with the reel driving mechanism is removed from the machine, the latter may be adjusted to operate in positions adjacent the roof of the mine chamber, as shown in Fig. 1.

When the mining machine is inclined to the position shown in Fig. 1, the operation is such as to form a roof having the shape of an arch, as shown at 166 in Fig. 2. When the mining machine frame 32 is held in a horizontal position, however, the roof of the mining chamber will be flat, as indicated at 167 in Fig. 3. Under some conditions the arch-shaped roof is more desirable as it forms a better support for the material above the chamber, but where such support is not necessary, the flat roof 167 may be preferred as the material may be more completely removed when this shape of the roof is formed. However, since the loop chain core-cutting mechanism and the plane kerf-cutter are disclosed and claimed in my co-pending application, Serial No. 121,359, I have herein shown only a sufficient portion of the mining mechanism to illustrate the utility of the mechanism for facilitating removal of used chain cutters both of the plane kerf-cutter and of the loop core-cutter.

Obviously those skilled in the art may make various changes in the details and arrangements of parts without departing from the spirit and scope of my invention as defined by the claims hereto appended and I wish therefore not to be restricted to the precise construction herein disclosed.

Having thus fully disclosed an embodiment of my invention, what I desire to have secured by Letters Patent of the United States is:

1. In a mining machine, the combination with a frame adapted to be attached to the frame of a mining machine having a flexible chain cutter, of superposed guideways on said frame for receiving a new chain cutter to be substituted for the chain cutter on the mining machine, and curved extensions at the opposite ends of said guideways for directing the chain with a reverse bending movement upon itself to facilitate the substitution of a new chain for the chain on the machine.

2. In an attachment for mining machines having chain kerf-cutters, the combination with a detachable frame, of longitudinal superposed guideways thereon for receiving a chain kerf-cutter for movement along said guideways in opposite directions, and upright curved supplemental guides at the opposite ends of said first-named guideways for directing the chain reversely in opposite directions of travel.

3. In an attachment for mining machines having chain kerf-cutters, the combination with spaced-apart supporting standards adapted to be attached to the framework of the machine, of spaced-apart longitudinal guideways mounted on said standards for guiding the chain from said kerf-cutter in opposite directions of travel, and curved guiding extensions at the opposite ends of said guideways to direct the chain reversely upon itself for travel alternately in opposite directions.
4. In a mining machine, the combination of an upright cutter chain frame, and detachable guide mechanism mounted in upright position for directing a cutter chain on to said frame at the upper portion thereof.
5. In a mining machine, the combination with a supporting frame, of a cutter chain frame mounted thereon in upright position, and a detachable chain guide mounted on top of said supporting frame in position to hold a chain supported thereby so that the end of said chain will be adjacent the chain on said frame and in position to be connected to the last-named chain.
6. A mining machine comprising a cutter chain, a frame on which said chain is mounted for sliding movement, a supplementary chain guide mounted in spaced relation to said frame, said guide comprising a pair of slideways arranged to hold a chain placed thereon with its ends adjacent the chain on said cutter chain frame but spaced therefrom to permit operation of said chain without removing said guide, so that a pair of links on said cutter chain may be disconnected from one another and connected to the end links of the chain on said supplementary guide, thus forming the two chains into an endless loop whereby said cutter chain may be replaced by the chain on said supplementary guide by causing said endless loop to travel about said cutter chain frame and said supplementary guide.
7. An attachment for mining machines having a chain kerf-cutter, comprising spaced-apart longitudinal guides superposed and with the forward end of the upper guide curved downwardly, a curved guide extension for the upper guide and located at the rear end thereof, and a curved guide extension for the lower guide and located at the forward end thereof.
8. In mining apparatus, the combination with a frame adapted to be detachably connected to a mining machine above a chain kerf-cutter therein, and means on said detachable frame for guiding a substitute chain-cutter downwardly from said frame while simultaneously guiding the used chain-cutter upwardly from the kerf-cutter onto said frame.
9. In mining apparatus, the combination with a kerf-cutter comprising a cutter-frame and a chain-cutter, of means for driving said chain-cutter, a stationary guide frame for a portion of the cutter-chain, and means for feeding said kerf-cutter while said frame remains stationary and while the chain travels thereon.
10. In mining apparatus, the combination with a supporting frame, of kerf-cutting mechanism comprising a cutter-frame and a chain-cutter adapted to travel thereon, a supplemental guide frame mounted on said supporting frame in position to guide and support a loop of the chain-cutter of said kerf-cutting mechanism, means for driving said chain-cutter to cause it to travel along said guide-frame as well as on said cutter-frame, and means for feeding said chain-cutter by moving said cutter-frame relatively to said supporting frame while said supplemental frame remains stationary relative to said supporting frame.
11. In a mining machine, the combination with a supporting frame, of a chain kerf-cutter mounted thereon for feeding movement relatively thereto, loop-extension guiding mechanism for the chain-cutter and mounted in fixed relation to said supporting frame, and means for driving the kerf-cutter including feeding movement thereof while the chain travels along said guiding mechanism.
12. In a mining machine, the combination with a chain kerf-cutter comprising an upright cutter-frame and a flexible chain-cutter adapted to be mounted thereon, and mechanism mounted in the upright plane of the cutter-frame for directing the chain-cutter in an upright direction onto said cutter-frame.
13. In a mining machine, the combination with a kerf-cutter comprising an upright cutter-frame and a flexible chain-cutter adapted to be mounted thereon, and mechanism above the kerf-cutter for either directing a chain-cutter onto said upright cutter-frame or directing the chain-cutter from said cutter-frame.
14. In a mining machine, the combination with a supporting frame, of a cutter-chain guide mounted thereon and comprising a trough curved downwardly at one end, and an additional cutter-chain guide spaced above the first-named guide and comprising a trough curved downwardly at both ends.
15. In a mining machine, the combination with spaced-apart supports adapted to be connected to the frame of a mining machine having a flexible chain kerf-cutter therein, and superposed spaced-apart cutter-chain guides mounted on said spaced-apart supports.
16. In a mining machine, the combination with a mining machine comprising a plane kerf-cutter having a cutter-frame and a

- chain-cutter adapted to be mounted thereon, of spaced-apart supports adapted to be mounted on said mining machine, superposed spaced-apart guides mounted on said supports in position for guiding a chain-cutter onto and off from said cutter-frame, said guides being adapted to receive a chain-cutter with newly sharpened bits for connection to a chain-cutter on said cutter-frame to form an endless chain extending around the cutter-frame and along said guides, and mechanism comprising means for driving the chain-cutter of a mining machine to move the chain-cutter of the mining machine from said cutter-frame and substitute therefor said chain-cutter with the newly sharpened bit.
17. In a mining machine, the combination with an upright kerf-cutter comprising an upright cutter-frame and a flexible chain-cutter mounted thereon, of means for driving said chain-cutter, and detachable mechanism adapted to be connected to the mining machine for removing the chain-cutter therefrom in an upright direction and substituting another chain-cutter therefor.
18. In a mining machine, the combination with an upright kerf-cutter comprising an upright cutter-frame and a flexible chain-cutter thereon, of means for supporting another chain-cutter in position to be substituted for the one on said cutter-frame, and mechanism for removing the chain-cutter on said cutter-frame and substituting therefor a chain-cutter on said support, by directing said chains along lines in an upright plane extending through said cutter-frame.
19. In a mining machine, the combination with a pair of reel carriers, of means for supporting said reel carriers in position to direct chain-cutters onto and off from a cutter-frame, and driving connections between said reel carriers.
20. In an attachment to mining machines, the combination with a supporting frame adapted to be connected to a chain kerf-cutter adjacent the cutter-frame thereof, of a pair of reels mounted on said frame, driving connections between said reels, and means for winding a cutter chain on one reel while paying out the cutter chain from the other reel.
21. In a mining machine, the combination with a pair of reels adapted to have wound thereon chain-cutters, of a pair of reel carriers adapted to be mounted on a mining machine having a chain-cutter in position to wind onto one of said reels, a chain-cutter on the other reel adapted to be unwound therefrom to take the place of the chain-cutter taken from the mining machine, and driving connections between said reel carriers to effect the winding of the chain-cutter on one reel while the chain-cutter on the other reel is being payed out.

22. In a mining machine, the combination with two reels each adapted to have wound thereon a chain-cutter, of means for supporting said reels on a mining machine in spaced-apart relation with their axes parallel, and speed compensating mechanism between said reels so that as a chain-cutter is unwound from one reel onto the other the winding tension on the chain will remain approximately uniform.

23. In a mining machine, the combination with a supporting frame adapted to be mounted on a mining machine in predetermined relation to a chain-cutter thereon, of a pair of reel carriers mounted on said frame, said reel carriers being adapted to receive reels one for paying out a chain-cutter and the other for receiving the chain-cutter on the mining machine, and yielding driving connections between said reel carriers for operating the reels to wind thereon the chain-cutter from the mining machine and unwind therefrom the substituting chain-cutter.

24. In a mining machine, the combination with a frame adapted to be mounted on a mining machine in predetermined relation to a chain-cutter thereon, of a pair of reel carriers mounted on said frame for rotation on parallel spaced-apart axes, driving wheels of different diameters connected to said reel carriers, and an additional wheel connected between said first-named wheels to transmit motion from one reel carrier to the other while reels on said reel carriers are being operated to wind up and pay out a chain-cutter from and to the mining machine.

25. In a mining machine, the combination with a supporting frame adapted to be detachably connected to a mining machine comprising a kerf-cutter having a cutter-frame and a chain-cutter mounted thereon, of a pair of spaced-apart reel carriers mounted on said supporting frame for rotation on parallel spaced-apart axes, a pair of reels mounted on said reel carriers, and an extra cutter-chain wound on one of said reels and adapted to be connected to a disconnected end of the chain-cutter on said cutter-frame, a flexible connection connected to the inner end of said extra chain-cutter and wound on and connected to the reel on which said extra chain-cutter is wound, another flexible connection connected to the other reel and wound thereon and having its free end adapted to be connected to the other disconnected end of the chain-cutter on said cutter-frame, means comprising the driving mechanism of the chain-cutter of the mining machine for unreeling the said extra chain-cutter from one of said reels while winding onto the other reel the chain-cutter on said cutter-frame to effect the substitution of the extra chain-cutter.

for the chain-cutter on said cutter-frame, and yielding driving connections between said reel carriers comprising compensating means for effecting an approximately uniform tension in the chains while being paid out from one of said reels and wound onto the other reel.

26. In a mining machine, the combination with a chain kerf-cutter comprising a cutter-frame and a chain-cutter thereon, of guiding mechanism for a loop extension of the chain-cutter, means comprising a sprocket for driving said chain-cutter when on said cutter-frame and on said guiding mechanism as a loop extension, and means for supporting said guiding mechanism so that the cutter-chain between the same and said sprocket will be bent back upon itself.

27. In a mining machine, the combination with a chain kerf-cutter comprising a cutter-frame and a chain-cutter, of means comprising a sprocket for driving said chain-cut-

ter, and guiding mechanism for the chain cutter to form an S-shaped double loop between said sprocket and the outer end portion of said cutter-frame.

28. In a mining machine, the combination with a supporting frame, of guiding mechanism mounted thereon in fixed relation thereto, chain kerf-cutting mechanism guided along said frame and comprising a cutter-frame and a chain-cutter thereon, and means for operating said kerf-cutting mechanism including feed thereof by moving said cutter-frame relatively to said supporting frame while said chain-cutter travels along said guiding mechanism and while the latter effects an S-shaped double loop between the outer portion of the cutter-frame and said operating means.

In testimony whereof I have signed my name to this specification on this 7th day of October, A. D. 1922.

EDMUND C. MORGAN.
